UNITED STATES PATENT OFFICE.

LELAND H. HILL, OF SWISSVALE, PENNSYLVANIA, ASSIGNOR TO WESTINGHOUSE ELECTRIC & MANUFACTURING COMPANY, A CORPORATION OF PENNSYLVANIA.

INDICATING DEHYDRATOR.

Application filed October 14, 1924. Serial No. 743,576.

My invention relates to fluid-insulated electrical translating devices and particularly to devices for preventing the access of moisture to the insulating fluid.

5 One object of my invention is to provide a device for chemically treating air or other gases entering an electrical translating device that shall indicate the condition of the chemical compound therein by showing the 10 relative position of the chemical compound within the device.

Another object of my invention is to provide a device for treating air or other gases that shall be unitary in form and adapted 15 to attachment to electrical translating devices already in service.

A further object of my invention is to provide a device that shall cause air or other gases passing there-through to traverse a 20 chemical compound that is movably-mounted in order to indicate its state of chemical exhaustion by giving a visual indication of the relative position of the chemical within the device.

25 In the accompanying drawings,

Figure 1 is a view, partially in elevation and partially in section, of an electrical translating device embodying my invention.

Fig. 2 is a view in elevation of the gas- 30 treating device embodying my invention.

Fig. 3 is a view, partially in elevation and partially in section, of the gas-treating device shown in Fig. 2.

Fig. 4 is a view, partially in elevation and 35 partially in section, of a regulator valve constituting a detail of the gas treating device.

My invention comprises, in general, an electrical translating device 1, such as a transformer, that is partially filled with insulating fluid 2, such as oil, above which 40 there is confined an atmosphere 3 of gas and a device 4 containing suitable chemical material for removing deleterious ingredients, such as water, from the air or gas drawn into the translating device 1 during the process of "inbreathing."

The gas-treating device 4 comprises a main casing 5 having a perforated top or cover member 6 and a bottom plate 7 that is 45 secured to the main portion 5 by screws 8. The main casing 5 is provided with suitable lugs 9 and 11 for securing the device 4 to the translating device 1. The bottom plate 7 is provided with a centrally-located, upwardly-extending apertured lug 12 and a down-

wardly projecting portion 13 that supports a threaded cap 14. The downwardly projecting portion 13 is provided with slots 15 behind which a transparent medium 16, such as glass, is mounted. The portion 13 is marked with suitable indicia, such as "full" and "refill", for cooperation with a pointer 27, in a manner hereinafter described.

Referring to Fig. 3, a coil spring 17 is mounted centrally of the upper surface of the bottom member 7 which, in turn, supports a container 18 for a chemical compound 19 that is confined by a porous member 20, such as a screen. In electrical translating devices, it is particularly desirable 70 that moisture be excluded from coming into contact with the insulating oil 2 for the reason that the presence of water in such oils lessens their dielectric properties and tends to create undesirable sludges therein. Accordingly, the container 18 is usually filled with a dehydrating compound, such as calcium chloride, although other chemical compounds may be employed, according to the 75 nature of the treatment desired to be given to the gas.

The central portion 21 of the container 18 is of cylindrical form and is free from the dehydrating compound 19. A pipe or duct 22 extends downwardly from the cover member 6 into the space 21 through the upper member 23 of the container 18 with which it has a sliding fit. Another pipe or duct 24 extends from the cover 6 to the gas space 3 in the translating device 1. The bottom 90 member 25 of the container 18 carries a centrally disposed rod 26 that terminates in a pointer 27 that cooperates with the indicia on the portion 13 for indicating the condition of the gas-treating device, in the manner hereinafter described.

Referring to Figs. 2 and 4, the gas-treating device 4 is provided with a regulating valve 31 that is attached to the casing 5. The regulating valve comprises two similar 100 check-valve units 32 both of which communicate with the interior of the casing 5 through an auxiliary chamber 33 constituting a portion of the casing 5. Each of the valve units 32 comprises a ball 34 that is 105 movable between a pair of seat members 35 and 36 in such manner that the force of gravity always tends to keep the ball 34 in cooperation with one of the seat members 35 and 36, thereby effectively closing the valve 110

to the passage of gas. The upper unit 32 is provided with a rain cap 37 for preventing the access of dust or moisture thereto.

Upon the occurrence of an increase in the volume of gas 3 contained in the electrical translating device 1, as by a reduction in the temperature of the constituent parts of the translating device 1, the pressure gradient between the atmosphere and the interior

10 of the casing 5 across the regulating valve 31 becomes sufficiently great to cause ball 34 of the lower unit 32 to be slightly lifted from its seat 36, thereby permitting a certain amount of air or gas to enter the chamber

15 33. This gas surrounds the screen walls 20 of the container 18, and the moisture carried in suspension by the gas is absorbed by the calcium chloride. Inasmuch as the electrical translating device 4 is connected di-

20 rectly to the pipe 24, which, in turn is connected to the pipe 22, the lower end of which is surrounded by the chemical compound 19, a pressure gradient exists across the latter. Accordingly, the gas surrounding the con-

25 tainer 18 tends to seep through the chemical compound 19 and enter the electrical translating device 1 through the ducts 22 and 24.

During the passage of the gas through the chemical compound 19, the latter undergoes 30 a certain amount of chemical decomposition or exhaustion that is recorded in the increase of its weight. The increased weight of the chemical compound 19 causes the spring 17 to be compressed, with the result that the

35 container 18 and the rod 26 settle relatively to the bottom member 7 of the device 5. The downward movement of the rod 26 causes the pointer 27 to assume successively lower positions behind the glass 16. By noting

40 the position of the pointer 27 between the indicia "full" and "refill" on the projecting portion 18, the operator is able to tell, at a glance, the degree of exhaustion of the chemical compound 19.

45 In the event that the pressure in the gas space 3 becomes greater than atmospheric pressure, a certain amount of gas is discharged through the duct 22 and the chamber 33 to the upper check-valve unit 32, the

50 ball 34 of which is lifted from its seat 35 to permit the escape of a quantity of gas to the atmosphere. While I have shown the two units of the regulator 31 to operate at the same pressure, it is obvious that, by

55 changing the area of the balls 34 in the seats 35 and 36 it will be possible to cause one unit to operate at a different pressure from the other, when it is desired that "inbreathing" of the electrical device 1 shall take

60 place at a lower pressure than "outbreathing".

It will thus be seen that I have provided a gas-treating device for electrical translating devices that is characterized by indicating the degree of exhaustion of the

chemical compound therein by showing the position of the chemical compound relative to its housing at all times.

It is understood that such various changes in the disposition of the parts shown in the accompanying drawings and described in the specification may be made as fall within the scope of the appended claims.

I claim as my invention:

1. A gas-treating device comprising a casing, a gas duct extending therein, a chemical container within the casing guided by the gas duct, means for movably supporting the chemical container and means for indicating the position of the container within the casing. 75

2. A gas-treating device comprising a casing, a gas duct extending therein, a chemical container within the casing surrounding the open end of the duct, and means for movably supporting the chemical container. 85

3. A gas-treating device comprising a casing, a gas duct extending therein, a chemical container within the casing surrounding the open end of the duct, means for movably supporting the chemical container and means for indicating the position of the container within the casing. 90

4. A gas-treating device comprising a casing, a gas duct extending therein, a chemical container within the casing surrounding the open end of the duct, means for movably supporting the chemical container, and means cooperating with the duct for controlling the gas movement through the casing. 95

5. A gas-treating device comprising a casing, a gas duct extending downwardly therein, a chemical container within the casing surrounding the open end of the duct, means for movably supporting the chemical container and means attached to the casing for cooperating with the duct for controlling the gas movement through the casing. 105

6. A gas-treating device comprising a casing, a gas duct extending therein, a chemical compound surrounding the open end of the duct, means for movably supporting the chemical compound and means for indicating the position of the chemical compound within the casing. 110

7. A gas-treating device comprising a casing, a gas duct extending therein, a chemical compound surrounding the open end of the duct whereby the gas traversing the duct is subjected to the chemical compound, means for movably supporting the chemical compound and means for indicating the position of the chemical compound within the casing. 120

8. A gas-treating device comprising a casing, a gas duct extending therein, a chemical compound, the weight of which changes with its chemical exhaustion, surrounding the open end of the duct whereby the gas traversing the duct is subjected to the chemical compound. 125

compound, means for movably supporting the chemical compound and means for indicating the position of the chemical compound within the casing.

- 5 9. A gas-treating device comprising a casing, a gas-duct extending therein, a chemical compound, the weight of which changes with its chemical exhaustion, surrounding the open end of the duct whereby the gas traversing the duct is subjected to the chemical compound, means for movably supporting the chemical compound and means for indicating the condition of the chemical compound by indicating its position within the casing.
- 10 15

10. A gas-treating device comprising a casing, a gas duct extending therein, a body of de-hydrating compound surrounding the open end of the duct whereby the gas traversing the duct is subjected to the de-hydrating compound, means for movably supporting the de-hydrating material and means for indicating the condition of the de-hydrating compound by indicating its position within the casing.

In testimony whereof, I have hereunto subscribed my name this 9th day of October, 1924.

LELAND H. HILL.
